DESIGN FOR A WHEEL

Paul W. Gaenssle, Detroit, Mich., assignor to
Budd Wheel Company, Philadelphia, Pa., a cor-
poration of Pennsylvania

Application September 16, 1933, Serial No. 49,271

Term of patent 14 years

To whom it may concern:

Be it known that I, PAUL W. GAENSSLE, a citizen of Germany, residing at Detroit, in the county of Wayne and State of Michigan, have invented a new, original, and ornamental Design for a Wheel, of which the following is a specification, reference being had to the accompanying drawing, which forms a part hereof.

Figure 1 is a perspective view of the wheel of my design.

Figure 2 is an enlarged fragmentary eleva-
tional view.

Figure 3 is an axial profile view.

I claim:

The ornamental design for a wheel substan-
tially as shown.

PAUL W. GAENSSLE.
